EGG CANDLING APPARATUS

Walter Austin Caswell, Winnipeg, Manitoba,
Canada

Application July 13, 1936, Serial No. 90,445

1 Claim. (Cl. 88—14.92)

The present invention relates to an apparatus for use in examining small objects to visibly determine their structural parts and more particularly to determine and ascertain imperfections in transparent or semi-transparent bodies such as eggs having amongst its principal objects the provision of an apparatus which will produce a beam of light of great intensity from an economically operated source of light.

5 The process of candling eggs calls for the examination of each egg by an experienced human eye with a light placed on the side of the egg opposite from the examiner's eye, such light to be of sufficient intensity as to render the egg so 10 being examined translucent. Other light rays should be excluded as far as possible; and to that end, it is customary to place the light within a container or other lamp housing, leaving an aperture through which a portion of the light rays 15 emitting therefrom will strike the egg being examined. A tinted lens covers the light-emitting aperture so as to produce a coloured light especially suitable for candling purposes and as it is necessary to employ a relatively strong light, the 20 candle power of the light source must be comparatively high when using such tinted lens; causing a great deal of unnecessary heat to be generated, the burning out of the lamp bulbs and 25 also involving considerable expense for the electric current consumed.

30 A further object of the invention is to provide an egg candling lamp which may be used in connection with a standard storage battery as well as with the ordinary lighting circuits with a minimum current consumption, producing a minimum degree of heat and yet produce a maximum light beam or a light beam with the required intensity for rendering eggs partially translucent, in order that an expert operator 35 may determine the quality and character of the eggs being examined.

40 A still further object of the invention is to provide a portable and self contained egg candling apparatus in which the source of light may be easily and readily focussed to give the light beam required and one which will be efficient in use and comparatively inexpensive in the cost of manufacture, thereby rendering the same commercially desirable.

45 Other objects of the invention will be in part obvious and in part pointed out hereinafter.

50 In order that the invention and its mode of operation may be readily understood by persons skilled in the art, I have in the accompanying

illustrative drawing and in the detailed following description based thereupon, set out an embodiment of the same.

In the drawing:

Figure 1 is a side elevation of the apparatus 5 embodying the present invention.

Figure 2 is a slightly enlarged view of the apparatus removed from its support and showing the lamp housing partially in section.

Figure 3 is a detailed sectional view, and 10

Figure 4 is a detailed sectional view taken on the line 4—4 of Figure 3 in the direction of the arrow points.

Referring now more particularly to the accompanying drawing wherein like and corresponding 15 parts are designated by similar reference characters throughout the several views, I have herein shewn a portable stand 1 which may be mounted upon a table or bench or any other device where the candling of eggs is to take place. This stand 20 1 has mounted therein a step-down transformer 2 which may be of any well known type having current supplied thereto from a plug-in cord 3. The stand 1 consists of a tubular standard 4 in which is slidably mounted a supporting rod or 25 handle 5. A set screw 7 is provided for retaining the rod 5 in its vertical adjusted position.

Carried by the upper end of this rod 5 is a 30 sectional lamp housing 8 comprising a substantially semi-spherical rear section 9 having a cylindrical sleeve 10 secured to and projecting therefrom. This sleeve 10 is rotatably supported within the split bearing 11 formed with the upper end of the supporting rod 5 and a locking bolt 12 connects the separated portions of this split bearing 35 for detachably connecting the sleeve 10 thereto. This sleeve 10 is also provided with an annular semi-circular groove 13 in which rests the bolt 12 in order to prevent the sleeve from moving longitudinally within the bearing 11 but permitting the sleeve 10 and the lamp housing carried 40 thereby to freely revolve therein.

Slidably mounted within the sleeve 10 is a 45 tubular electrical socket 14 of a conventional type having a plug 15 detachably connected to one end thereof and this plug 15 carries a suitable conductor 16 which latter is connected to the transformer 2. Detachably supported within the opposite end of the socket 14 is a lamp 17. 50 This lamp is preferably a six-volt automobile headlight bulb and when connecting the same to a lighting circuit, the transformer 2 is employed, but in case the lighting circuit is not available, the transformer 2 may be removed 55

from the stand 1 and an ordinary storage battery substituted therefor which should give the required current for the type of lamp 17 employed.

Secured to and depending from the socket 14 is a bracket 18 having an apertured lower end through which projects a stud-bolt 19 having one end permanently attached to the supporting rod 5. Carried by this bolt 19 is a locking nut 20 and an adjusting nut 21 and from this construction it is quite obvious that the socket 14 together with its bracket 18 may be adjusted longitudinally within the sleeve 10 and yet be retained in such adjusted position. The outer section 22 of the housing has a light emitting opening formed therein which is covered by a lens 23. This lens is preferably made from a green tinted glass as this latter color has been approved as most acceptable for the candling of eggs. A spring controlled locking device 24 is carried by the section 22 of the housing and retains the lens 23 within the light emitting opening thereof. Surrounding this light emitting opening of the section 22 is a hood 25. The outer face of the hood 25 as well as the section 22 of the casing is preferably painted black or the same may be made from a black hardened rubber in order that the eggs to be tested may be placed in front of the hood 25 and prevent any refracted or reflected rays of light coming from the housing to strike the eggs, thereby causing a concentrated beam of light to be directed upon the egg being so examined. The rear section 9 of the lamp housing has slotted brackets 26 projecting therefrom which are to be engaged by the pins 27 carried by the outer section 22 of the lamp housing, whereby the two sections of the lamp housing may be detachably connected.

The rear section 9 of the lamp housing has formed therein two openings similar to the opening 28 shewn upon the drawing, which act as vent openings for permitting the heat generated by the lamp 17 within the housing to escape therefrom and at the same time, light rays from the lamp 17 will be projected through these openings 28. Permanently attached to the housing is a handle 29 whereby the housing may be manually rotated within the split bearing 11. By the rotation of this housing, the openings 28 will be positioned adjacent to the lower end thereof or as shewn in the drawing, whereby the light rays from the lamp 17 may be projected downwardly upon the support 1 or the table or bench upon which it is mounted in order that the operator will be supplied with light upon the eggs or

other articles positioned upon such a table or support. An egg candling device of the character described is of course to be used in a darkened room and by reversing the position of the openings 28 the light from the lamp may be projected at other angles throughout the room for illuminating purposes and yet no direct rays of light will be projected from the forward end of the lamp housing as would come in contact with the examiner's eyes or the eggs being examined.

The inner wall of the section 9 of the lamp housing is preferably of a parabolic configuration and highly polished in order to serve as a reflector and due to this design of reflector the rays of light from the lamp 17 will be concentrated and reflected through the lens 23 in a strong beam of light. In order to regulate the intensity of this beam of light, the lamp 17 may be focussed with respect to the lens 23 by longitudinally moving the lamp socket 14 within the sleeve 10. When the desired focus has been obtained, the socket 14 may be locked in its adjusted position.

Manifestly, the construction herein shewn is capable of considerable modification and such modifications as come within the scope of my claim, I consider within the spirit of my invention.

I claim:—

An egg candling device comprising in combination a sectional casing consisting of a semi-spherical rear section and an outer section, means for detachably connecting the sections of the casing together, a cylindrical sleeve formed with and projecting from the axis of said rear section, supporting means, means for rotatably mounting said sleeve within said supporting means, a lamp arranged within said semi-spherical rear section and adjustably mounted within said sleeve, a lens covered opening formed within said outer section and arranged in a path contiguous with that of the axis of said semi-spherical rear section, a hood projecting from said outer section and encircling said lens covered opening thereof, whereby a concentrated beam of light may be directed upon an egg to be examined when placed in front of said hood, said semi-spherical section having light emitting openings formed therein whereby rays of light from said lamp may be used for illuminating purposes, and a handle secured to said casing whereby the latter may be manually rotated upon said support for causing the rays of light passing through the openings of said semi-spherical section to be projected at various angles.
